(57) **CLAIM**

The ornamental design of a time clock, as shown and described.

DESCRIPTION

FIG. 1 is a perspective view of a time clock showing our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The dashed broken lines in the drawings show portions of the time clock that form no part of the claimed design.

The rear view of the article is not shown in the drawings or described in the specification. It is understood that the appearance of any part of the article not shown in the drawings or described in the specification forms no part of the claimed design. As such, the determination of patentability is based on the design for the article shown and described.
